CLAIM

The ornamental design for a jewelry setting, as shown and described.

DESCRIPTION

FIG. 1 is a perspective view of a jewelry setting showing my new design;

FIG. 2 is a right side elevational view, the left side elevational view being a mirror image thereof;

FIG. 3 is a top plan view thereof;

FIG. 4 is a bottom plan view thereof;

FIG. 5 is a rear elevational view thereof;

FIG. 6 is a perspective view of the jewelry setting of FIG. 1 in an alternative environment.

FIG. 7 is a right side elevational view of FIG. 6, the left side elevation view of FIG. 6 being a mirror image thereof; and, FIG. 8 is a front elevational view of FIG. 6.

The broken line showing of parts of the drawings is included for the purpose of illustrating use and environment and forms no part of the claimed design.
